UNITED STATES PATENT OFFICE.

WILLIAM L. STRINGER, OF COOPERSTOWN, NORTH DAKOTA.

HAME-TUG.

SPECIFICATION forming part of Letters Patent No. 787,229, dated April 11, 1905.

Application filed July 22, 1904. Serial No. 217,698.

To all whom it may concern:

Be it known that I, WILLIAM L. STRINGER, a citizen of the United States, residing at Cooperstown, in the county of Griggs and State of North Dakota, have invented a new and useful Hame-Tug, of which the following is a specification.

This invention relates to hame-tug attachments to harness, and has for its object to improve the construction and increase the strength, durability, and efficiency of such devices, while at the same time decreasing the expense of construction.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the drawings thus employed, Figure 1 is a plan view of the improved device. Fig. 2 is a front elevation. Fig. 3 is a transverse section on the line 3-3 of Fig. 2. Fig. 4 is an enlarged sectional detail of the hame-clip. Fig. 5 is a perspective view of the back-band and girth-coupling portion of the device. Fig. 6 is a perspective view of a modified form of the hame-coupling clip detached. Fig. 7 is a perspective view of a modified form of the back-band and girth-clip coupling detached. Figs. 8 and 9 are detached perspective views of two modified forms of detachable draft-trace-holding pins.

The improved device comprises a base-frame 10, having lateral ribs 11 12 longitudinally of its upper and lower edges and provided with spaced apertures 13, disposed in vertical aline-

ment, as shown. The rear face of the frame 10, or the face which comes next to the horse, will be rounded or oval-shaped, as shown in Fig. 3, to prevent discomfort to the animal.

Pivoted, as at 14, between the forward ends of the ribs 11 12 is a link 15, and mounted to swing vertically upon this link is a coupling means by which connection is made with the hames, this coupling means consisting of two plates 16 17, spaced apart and hinged together at one end, as at 18, and with half-sockets 19 20 in the two plates adjacent to the hinge for engaging the bar of the hames, which is not illustrated, as it forms no part of the invention. The opposite end of the plate 16 is provided with a stud 23 for passing through an aperture in the free end of the link 15 and likewise through an aperture in the other plate, 17, in which it is secured, as by riveting. By this simple means the base member 10 is adapted to be coupled flexibly to the hames in position to swing both vertically and laterally, as will be obvious.

Pivoted to the ribs 11 12 at the rear end of the base member 10 is a coupling means whereby the back and girth portions of the harness are connected, this coupling consisting of a frame having spaced side members 24 25, pivoted, as at 26 27, to the side ribs 11 12 and provided with longitudinal apertures 28 29 and connected intermediately by a bar 30 and also connected at their rear ends by a laterally-extending loop 31. The bar 30 is furnished with a central lug 32, provided with a transverse aperture 33, the apertures 28 29 to receive the billet of the back-band of the harness, a portion of which is indicated at 34, and the lug 32 to pass through an aperture in the billet and be held therein, as by a pin 36 through the aperture 33. The draft-trace, a portion of which is represented at 39, is passed beneath the loop 31 and is disposed between the ribs 11 12 and in engagement with the outer face of the base member 10 and has secured between its layers at its inner terminal a trace-eye 40 to receive a pin 41, passed through a pair of the aligned apertures 13. By this means the draft-trace may be adjusted longitudinally of the base member 10 by set-

ting the pin 41 in any desired pair of apertures 13 to lengthen or shorten the draft-trace, as will be obvious.

One or more guard-loops 42 will be attached 5 to the base member by short rivets through the ends of the loops and the apertures 13 to support the draft-trace and prevent lateral displacement of the same.

The pin 41 must be easily and readily de- 10 tachable to enable the draft-trace to be quickly adjustable, and the pin must also be held in engagement with the base-frame with sufficient firmness to prevent accidental displacement when the device is in use. An approved 15 holding means consists of a spring-catch 45, riveted to a plate 45^a, secured to the eye member 40, and with one end 46 bent at right angles to its length and crocheted to straddle the upper or head end of the pin 41 and hold it 20 yieldably in position. The spring-catch 45 will possess sufficient force to hold the pin against accidental displacement from the severe jarring and shaking about to which it will be subjected when the harness is in use 25 or when thrown about when not in use, while at the same time readily yieldable to a force applied for its detachment when the trace is to be adjusted. If preferred, a wire spring 47 may be substituted for the flat spring 45, 30 as in Fig. 8, or a rubber band or strip 48 may be employed, as in Fig. 9, if required.

When the improved device is attached to harness having an eye or loop on the hames

instead of the ordinary bar, the form of clip shown at 50 in Fig. 6 will be employed, and a simple loop 49 may be substituted for the more elaborate coupling means at the rear end of the base member 10, if preferred.

It will be noted that a simply-constructed and strong and durable device is produced by means of which the draft-trace can be quickly and easily adjusted and which will not annoy and irritate the draft-animals or increase their burden or labor.

Having thus described the invention, what is claimed is—

In a hame-tug, a base-frame having spaced lateral side ribs, means for adjustably connecting the draft-trace between said side ribs, detachable means for connecting the base-frame to the hames, a coupling-frame movably connected to the rear end of said base-frame and provided with a loop beneath which the draft-trace passes and having a transverse central bar provided with a central lateral stud for passing through the back-band and girth members of the harness, said stud having a transverse aperture for receiving a holding-pin.

In testimony that I claim the foregoing as my own I have hereto affixed my signature in the presence of two witnesses.

WILLIAM L. STRINGER.
